(57) **CLAIM**

The ornamental design for a divided half flap auto-bottom carton, as shown and described.

DESCRIPTION

FIG. 1 is a top rear right perspective view of a divided half flap auto-bottom carton in an expanded state, showing our new design;

FIG. 2 is a top view of the design shown in FIG. 1;
 FIG. 3 is a bottom view of the design shown in FIG. 1;
 FIG. 4 is a left side view of the design shown in FIG. 1;
 FIG. 5 is a right side view of the design shown in FIG. 1;
 FIG. 6 is a rear view of the design shown in FIG. 1;
 FIG. 7 is a front view of the design shown in FIG. 1; and,
 FIG. 8 is a perspective view of the design in FIG. 1 in an assembled state.

The broken lines shown in the figures are included for the purpose of illustrating portions of the divided half flap auto-bottom carton and form no part of the claimed design.
